UNITED STATES PATENT OFFICE.

WILLIAM S. MALLORY, OF BATAVIA, NEW YORK.

IMPROVEMENT IN RAILROAD-RAIL SUPPORTS.

Specification forming part of Letters Patent No. 42,586, dated May 3, 1864.

To all whom it may concern:

Be it known that I, WILLIAM S. MALLORY, of the town of Batavia, in the county of Genesee and State of New York, have invented a new and Improved Combination Rail Support and Connection for the Ends of the Rails on Railroads; and I do hereby declare that the following is a full and exact description thereof, reference being had to the accompanying drawings, and to the letters of reference marked thereon.

Plate 1, Figure 1, is a plan view of said rail support and connection. In all the figures of the different plates the lines in red ink represent parts concealed from view. Fig. 2 is a side view, and the dotted line running through both figures is designed to show a sectional cut. Fig. 3 is a sectional view across the center, and Fig. 4 is an end view. Plate 2, Fig. 1, is a representation, side view of a portion of said rail support and connection, leaving out all not represented here; and Fig. 2 is an end view of the same, but showing the device for supporting and connecting the rails as placed on both sides of the rails. Plate 3, Fig. 1, is a plan view of said rail support and connection, leaving out all not represented here. Fig. 2 is a sectional view of the same, and Fig. 3 is an end view. Plate 4, Fig. 1, is a plan view of said rail support and connection, leaving out all not represented here. Fig. 2 is a sectional view of the same, and Fig. 3 is an end view.

To enable others skilled in the art to make and use my invention, I will proceed to describe its construction and operation.

The base plate, letter *a*, upon which the structure rests, is made of wrought or cast iron, about one-half of an inch thick, one foot long, and about eight inches wide, and is placed transversely to the rails, and rests upon the ground, or upon one of the sleepers or cross-ties of the road, to which it is fastened by bolts or screws or a screw-bolt. A portion of the surface at one end is corrugated. I attach to this base-plate two jaws, made, either of cast or wrought iron, in the form represented by letter *b*, Fig. 4, Plate 1, by means of screws, so that the base-plate serves as a nut for the screw. The bottom of one of said jaws is corrugated, and rests upon the corrugated surface of the plate, to which it is fastened by screws in slotted holes, so that the same may be adjusted closely to the rails or the side pieces attached to the rails; and upon the face of each

jaw rollers or balls are inserted, so as to prevent friction between said jaws and rails and allow free expansion and contraction. These jaws are so constructed and arranged as not to cramp the flanges of the rails and break them.

I make a shoe fitted to the bottom of the rail, with flanges on each side rising vertically a little higher than the flanges of the rails, or it may be made and used without any flanges, and may have rollers on the bottom rising a little higher than the surface of the bottom, so that the rail can expand and contract freely, and this shoe may be continued the whole length of the road, and thus form a continuous rail. This shoe is distinguished by letter *f*. Inside of the flanges of this shoe *f*, I place a thin flat metallic shoe without any flanges, letter *g*, upon which rest the bottom of the rails, and the rails are jointed together in the form and manner represented in Fig. 2 of Plate 3, so that they will rest and bear upon each other at the ends.

Upon the top of the flange of the shoe *f*, or upon the flange of the rail, I place a bar or plate with one or more rollers, and I then fasten said shoe to the base-plate or a cross-tie by a screw-bolt or spike having a head with rollers upon the under side which shall project over said plate or bar, arranging the same so as not to cramp the flange of the rail and cause it to break. This bar or plate extends from one rail to the other, and is fastened to each, and by this means I break the joint and secure a free action, and allow the rails to expand and contract, and at the same time hold them fast. When this last-described arrangement is used, I bolt the rail firmly to the tie at its center and allow it to contract and expand each way therefrom. The head of the screw-bolt with rollers is designated by letter *g*, and the flange of the shoe with the bar or plate by letter *h*, Fig. 1, Plate 1. I also support and connect the ends of the rails by means of a metallic bar, which may be round or otherwise, firmly bolted to the side of the end of one rail and fitted thereto, and extending beyond the end of the other rail from one to two feet, and entering a tube or any open fastening on the side of the end of the other rail, so constructed as to fit each other. The tube may be of gas-pipe, and fastened to the rail by rings, or it may be slotted and held

by a T-bolt. Upon the opposite side of the rail a corresponding arrangement may be used with the tube and bar reversed—viz., the tube being opposite to the bar, and the bar on the other rail opposite to the tube. The tube and bar are represented by the letter h^2 , Fig. 2, of Plate 1, and are more fully illustrated by Plate 2. I also attach on each side of the rails two side pieces about twenty inches long, of metal or wood, which are fitted to the hollow part of the rail, and braced at the bottom against the flange of the bottom shoe, f . They are distinguished by the letters i and k , the former being upon the inside and the latter upon the outside, of the rail. Upon the inside of the side piece, k , is a depression for the action of a roller or ball inserted in the rail, or the roller may be placed in the side piece. There is also inserted in the rail a roller extending through the same, so as to be operated by the side pieces on each side. This roller is distinguished by the letter l . The side pieces are held to the rails and bottom shoes in part in the following manner: I bolt the flange of the rail on each side to the bottom shoes by two bolts having rollers upon each to prevent friction, extending vertically upward, and having eyes upon the top of each, through which passes a bolt or rod extending through a roller on the rail and through the side pieces, and secured by a nut. The vertical bolts are secured by nuts under the bottom of the shoe, screwed down upon a cross-piece or the shoe, and this cross-piece has a place in the center for a set-screw, so as to be able to tighten the same to the shoe. The vertical bolts are represented by letter m , and the cross bolt by letter o , the set-screw by letter n . (Fig. 4, Plate 1.)

In the bottom of the rail or rails I place one or more rollers, distinguished by letter p , Fig. 2, of Plate 1. On the flanges of the bottom shoe, or from the side of the shoe when there are no flanges, I make an ear on each side, extending up high enough, so that a bolt may pass through the ears and slotted holes in the side pieces and rails, designated by letter r , Fig. 1, Plate 1. (With these ears and bolts rails may be held and connected by using the required number. The ear is marked letter r^2 , Fig. 2 of Plate 1. I also bolt to the base-plate a , or to a cross-tie, two metallic arms, one on one side, extending up, and then horizontally through a slotted hole in the rail, and through an eye on the top of the other arm, which extends up to the rail on the other side, and is secured by a nut, and by this means the rail is firmly held, and by the use of these arms thus arranged with others the rails will be supported and connected. These arms are distinguished by letter s , and the bolts which bolt them to the base-plate by letter t . I also connect and support the ends of the rails by two bolts extending up through the bottom of the shoe on each side of the rail, with an eye on the top of one and the other bent and forming an elbow, and passing through

the side pieces and rail, and secured and tightened by a nut. The bolt is provided with a roller where it rests against the side pieces to prevent friction. These bolts are distinguished by letter u .

Plate 2 illustrates and represents a part of the above-described combination rail support and connection, as the same may be used practically without the other parts, and Plates 3 and 4 are like illustrations of parts of said invention.

Having thus described my invention and its construction and operation, what I claim, and desire to secure by Letters Patent, is as follows:

1. The construction of a rail chair or support to the rails, having adjustable jaws that can either be attached to the sleepers or to a base-plate, and the latter fastened to the sleepers, when said jaws, or one of them, is held and retained in position by means of corrugations upon the bottom portion of them, fitting to corresponding corrugations upon the base-plate, and made adjustable by means of a set-screw and slot in the jaws, and when the upper and inner ends, coming in contact with the rails, are furnished with rollers, in the manner and for the purposes set forth.
2. The construction of a shoe for the reception of the rails with flanges on each side thereof to prevent lateral movement, on one of which flanges a bar extending across the joints of the rails, in which rollers are placed to prevent friction, said shoe, or the flanges of the rail, if desired, when no shoe is used, being held in position upon the chair or sleeper by means of screws or spikes with rollers in the head thereof, so adjusted as to hold either the shoe or the rail in the manner and for the purpose set forth.
3. Placing a roller or rollers in the sides of the rails, and also in the bottom of the same, arranged and constructed as described, and for the purposes set forth.
4. Supporting the ends of the rails and connecting them together by means of hollow tubes, slotted or otherwise, and secured to the rails by rings or in any suitable manner, constructed and arranged substantially as described, and for the purposes set forth.
5. Supporting and connecting the ends of rails by means of side pieces on each side, extending across the joints, with rollers inserted therein and bolts passing through slotted holes in said side pieces, and also in the rails, constructed and arranged as described, and for the purposes set forth.
6. Securing and holding rails fast to a cross-tie at the ends, and also near the longitudinal center thereof, by means of the arms s , bolted through the rail and secured to the tie, as described.
7. Making the bottom shoe with or without vertical flanges, and holding the rails thereto by means of the said side pieces, a cross-plate under said shoe, with bolts passing through holes in the same near each end, with nuts

under the bottom, forming a kind of stirrup, and said bolts passing up through the shoe, one of said bolts being in the form of an elbow, passing through said pieces and rails, and an eye upon the top of the other bolt, secured by a nut, said bolts having rollers on the side bearing against said side pieces, and also bolts passing through the shoe with or without the said cross-piece upward between the side pieces and the rails, with rollers on the same with two eyes on the top, through which a cross-bolt passes on a roller, and secured by a nut, and thus allowing free action, but still holding the rails firmly to the shoe, and also the means of tightening the same by the

set-screw *n*, the whole combined and arranged as herein set forth and described.

8. The combination and use of rollers, balls, and wheels with the rails and side pieces, bases or supports, for the purpose herein set forth, and substantially as described.

9. Sustaining the ends of the rails by the jogs on each end thereof, in combination with the side pieces and the bolts and fastenings *u u*, substantially as described, and for the purposes set forth.
